COMBINED TROPHY AND TROPHY SUPPORT

Dorothy K. Allen, Libertyville, Ill., assignor to F. H. Noble & Company, Chicago, Ill., a corporation of Illinois

Filed Nov. 15, 1967, Ser. No. 9,427

Term of patent 14 years

Int. Cl. D11—02

U.S. Cl. D29—28

FIG. 1 is a perspective view of a combined trophy and trophy support showing my new design;

FIG. 2 is a somewhat enlarged front elevational view of the combined trophy and trophy support shown in FIG. 1;

FIG. 3 is a somewhat enlarged side elevational view of the combined trophy and trophy support shown in FIG. 1;

FIG. 4 is a top plan view of the combined trophy and trophy support shown in FIG. 2;

FIG. 5 is a bottom plan view of the combined trophy and trophy support shown in FIG. 2; and

FIG. 6 is a sectional view taken along the line 6—6 of FIG. 2.

The dominant features of my design are shown in full lines.

I claim:

The ornamental design for a combined trophy and trophy support, substantially as shown and described.
